PUTTER

J. E. Luther Morris, 5925 W. Cataline Drive,
Phoenix, Ariz. 85033

Filed Mar. 17, 1971, Ser. No. 125,455

Term of patent 14 years

Int. Cl. D21—02

U.S. Cl. D34—5 GC

FIG. 1 is a perspective view of a putter embodying my new design.

FIG. 2 is a toe end elevation of the putter head.

FIG. 3 is a top view of the putter head.

FIG. 4 is a side elevation of the putter head, looking at the putter from the rear.

FIG. 5 is a side elevation of the putter head looking toward the striking face.

The shaft is shown fragmentarily in FIGS. 2 through 5 for convenience of illustration.

I claim:

The ornamental design for a putter, as shown and described.
